CABINET FOR ELECTRONIC EQUIPMENT

Seton Cottier, Woodstock, Clarence F. Graser, La Grange,
and John E. Stork, Woodstock, N.Y., assignors to International
Business Machines Corporation, New York,
N.Y., a corporation of New York

Filed Apr. 6, 1964, Ser. No. 79,351

Term of patent 14 years

(Cl. D26—5)

FIG. 1

Des. 205,067

PAGE 2

FIG. 2

FIG. 3

FIG. 1 is a front, right and top perspective view of a cabinet for electronic equipment, showing our design.

FIG. 2 is a front, left and top perspective view of the design of FIG. 1.

FIG. 3 is a rear view of the design of FIG. 1.

Portions of FIGS. 1 and 2 are diagonally lined to indicate transparency.

We claim:

The ornamental design for a cabinet for electronic equipment, substantially as shown and described.
